DESIGN FOR A COMBINED REFLECTOR BULB AND STAND

Raebelle Wagner, Freehold, N. J.

Application August 12, 1944, Serial No. 114,848

Term of patent 14 years

(Cl. D48—20)

To all whom it may concern:

Be it known that I, Raebelle Wagner, a citizen of the United States, residing in Freehold, county of Monmouth, and State of New Jersey, have invented a new, original, and ornamental Design for a Combined Reflector Bulb and Stand, of which the following is a specification, reference being had to the accompanying drawing, forming a part thereof.

In the drawing:

Fig. 1 is a front view of the combined reflector bulb and stand, showing my new design.

Fig. 2 is a top plan view of the article shown in Fig. 1.

The side opposite that shown in Fig. 1 is the same as that illustrated in the figure.

I claim:

The ornamental design for a combined reflector bulb and stand, as shown and described.

RAEBELLE WAGNER.
